Primary Examiner—Freda Nunn

[57] CLAIM

The ornamental design for a portable word processor that can be snapped onto the parallel of a drawing board, as shown and described.

DESCRIPTION

FIG. 1 is a top plan view of the portable word processor that can be snapped onto the parallel of a drawing board showing my new design;

FIG. 2 is a bottom plan view thereof;

FIG. 3 is a left side elevational view thereof;

FIG. 4 is a right side elevational view thereof;

FIG. 5 is a rear elevational view thereof; and,

FIG. 6 is a front elevational view thereof.

The broken lines are shown in the views for illustrative purposes only and form no part of the claimed design.
